UNITED STATES PATENT OFFICE.

KATHARINE MEYER, OF CARLSTADT, NEW JERSEY, ASSIGNOR TO OSWALD MEYER,
OF CARLSTADT, NEW JERSEY.

EXPANDING FRAME FOR EMBROIDERY-MACHINES.

1,397,322.

Specification of Letters Patent. Patented Nov. 15, 1921.

Application filed November 19, 1919. Serial No. 339,148.

To all whom it may concern:

Be it known that I, KATHARINE MEYER, a citizen of the United States, residing at Carlstadt, county of Bergen, and State of New Jersey, have invented certain new and useful Improvements in Expanding Frames for Embroidery-Machines, of which the following is a specification.

This invention relates to an improvement 10 in the detachable frames employed in embroidery machines to hold the fabric to receive the embroidery in a stretched position to have the pattern embroidered thereon.

The invention has for an object to provide a novel and simple type of embroidery frame characterized by ease of application and removal of the fabric.

For further comprehension of the invention, and of the objects and advantages 20 thereof, reference will be had to the following description and accompanying drawings, and to the appended claim in which the various novel features of the invention are more particularly set forth.

Figure 1 of the drawings is a face view 25 of an embroidery frame constructed according to the invention.

Fig. 2 is an enlarged transverse section on the line 2—2 of Fig. 1.

Fig. 3 is an enlarged detail transverse section on the line 3—3 of Fig. 1.

Fig. 4 is a detail section on the line 4—4 of Fig. 1.

Fig. 5 is a detail horizontal section on 35 the line 5—5 of Fig. 1.

Figs. 6 and 7 are fragmentary vertical sections illustrating the method of securing the fabric in place.

As here shown my improved frame 40 comprises the upper and lower main horizontal rails 1 and 2 which may be made of wood. These rails are rigidly joined together by the vertical metal straps 3 which are bent at their ends as at 4 to project across the 45 top and bottom faces respectively of the rails and may be secured thereto by screws or by any suitable means.

Disposed between and parallel to the rails 1 and 2 are a pair of intermediate bars 5 50 and 6 which extend behind and are secured to the straps 3 at their ends to slide longitudinally of the latter, or toward and away from the said rails. The means by which I secure these intermediate bars to the straps

3 is illustrated more particularly in Fig. 5 55 and comprises the metal strips 7 which are secured at one end by screws 8 to the front faces of the bars and have each a raised portion 9 which is spaced from the bars and projects over the vertical straps 3. The other 60 ends of these strips are bent back across the end faces of the bars as at 10 and finally turned in behind the bars as at 11, screws such as 12 passing through these inturned portions and into the bars. The bars are 65 adjustably secured to the straps 3 by means of headed pins 15 passing through suitable registering openings in the strips and the ends of the bars and through the desired ones of the series of holes 16 spaced longitudinally of each of the straps.

Extending along the upper rail 1 and secured thereto by screws 17 is a metal strip 18, this strip being mounted on the beveled off or inclined lower portion 1' of the bar 75 so that the strip is completely offset from the straps 3. The strip 18 has an outwardly curved lower edge 18' to which is fixed a row of pins 19 which extend upwardly over and parallel to, the body of the strip.

A similar, and similarly arranged strip 20 is fixed by screws 21 to the adjustable intermediate bar 6, this strip having the outturned edge 20' and upwardly projecting pins 22.

Extending along the adjustable bar 5 and secured thereto by screws 25 is an elongated clip member 26 which projects toward the top rail 1, this projecting portion being offset inwardly of the straps 3 and being doubled back upon itself as at 26'. Within the channel formed in this clip member is inserted a flat bar 27 having a rubber covering 28 which may be formed by a rubber tube, this bar serving to hold the fabric in place as will be presently pointed out. A pair of latches 29 having their ends notched as at 29^a are pivoted on the upper pair of strips 7 and are adapted to be swung into engagement with the projecting ends of the bar 27 to hold the latter in place.

Extending along the lower rail 2 is a second elongated clip member 30 this member being offset to clear the straps similarly to the strips 18 and 20 and clip member 26, and being secured in place by screws 31. The upper and lower edges of this clip member are doubled back as at 30' and 30^a the

doubled back portion 30^a being shorter than the portion 30'. A flat bar 32, similar to the bar 27, and having a similar rubber covering 33, is adapted to hold the fabric in 5 this clip member.

In securing on the frame a fabric to be worked, the top edge of the fabric 34 is hooked on the pins 19 and the lower edge wrapped around the rubber covered bar 27, 10 the latter is then inserted into position in the clip member 26 as shown in Fig. 6 and the latches 29 swung to engage the ends of the bars 27. The bar 5 is then pressed downwardly along the straps and when the fabric 15 is properly stretched the pins 15 are inserted into place through the registering ones of the holes 16.

A different fabric 35 may be hooked at its upper edge over the pins 22 and have 20 its lower edge wrapped around the rubber covered bar 32. The latter is then inserted in the clip 30 in the direction indicated by the arrow 36 in Fig. 7, the difference in length of the doubled back portions 30' and 25 30^a permitting the bar to drop in past the portion 30^a, the stretching of the fabric pulling the lower edge of the bar down under said portion 30^a, the upper edge being held by the portion 30'.

30 It will be understood that the main rails 1 and 2 may be of any suitable length and a series of frames arranged therealong.

The manner of use of the frame will be apparent from the above description. When 35 one frame is removed from the machine to have a new fabric stretched thereon, a sec-

ond frame with the fabric thereon may be inserted in its place on the machine.

It is to be understood that I may combine or arrange the various fabric holding devices otherwise than as here shown, it not being essential that the clips 26 and 30 should be on the movable and fixed bars respectively, or other variations in the arrangement may be made. 40 45

Having thus described my invention what I claim as new and desire to protect by Letters Patent of the United States is as follows:

An embroidery frame comprising a pair 50 of fixed parallel rails, straps connecting said rails, a bar extending between said straps and secured thereto to be adjustable therealong, and fabric holding devices mounted on one of said rails and said bar, 55 said fabric holding devices comprising an elongated clip member having one edge extending backwardly over the body thereof, a flat bar adapted to be inserted under the said backwardly extending edge, a tubular 60 rubber covering for said last mentioned bar, the said last mentioned bar being longer than the said strip and cover to cause the ends thereof to project therebeyond, and hinged latches mounted on the first men- 65 tioned bar and adapted to engage the projecting ends of the second mentioned bar, for the purpose set forth.

In testimony whereof I have affixed my signature.

KATHARINE MEYER.
